(57) **ABSTRACT**

A terry fabric having a top surface and a bottom surface. The top surface includes a first yarn having a first pile weight. The top surface has a first surface weight. The bottom surface includes a second yarn having a second pile weight. The bottom surface has a second surface weight. The first yarn is coarser than the second yarn, and the first pile weight is greater than the second pile weight. The first surface weight is greater than the second surface weight. A combined weight of the top surface and the bottom surface of the terry fabric is less than two times the first pile weight but greater than the second pile weight.

FIG. 5

TERRY FABRIC HAVING SURFACES WITH VARYING PILE WEIGHTS

CROSS-REFERENCE TO RELATED APPLICATION

This application claims the benefit of U.S. Provisional Patent Application No. 62/802,026, filed Feb. 6, 2019, which is hereby incorporated by reference in its entirety.

FIELD OF THE DISCLOSURE

The present disclosure relates generally to fabrics, and more specifically, to a terry fabric having surfaces with varying pile weights.

BACKGROUND

Terry fabrics have traditionally been used for making towels due to their durability and ability to absorb water. However, terry fabrics are difficult and expensive to launder because of these qualities. Laundering terry fabrics effectively calls for significant amounts of detergent, water, and heat or drying time compared to other fabrics. To overcome these challenges, it has been desirable to reduce the overall weight of the fabric, and thus, the weight of the towel. However, in traditional terry fabrics, the weight of pile is distributed evenly between the two faces of the fabric, i.e., 50% pile weight on one face of the fabric and 50% pile weight on the opposite face of the fabric. In other designs, a single face of the fabric may have pile weight distributed differently (e.g., in bands with varying pile weights across the face of the fabric). However, this affects the overall appearance and feel of the fabric, and it also limits the versatility of the fabric during manufacturing by, for example, limiting what borders might be used on the fabric based on the pile weight distribution.

The present disclosure is aimed at solving one or more of the problems identified above.

BRIEF DESCRIPTION OF THE DRAWINGS

Advantages of the present disclosure will be readily appreciated, as the same becomes better understood by reference to the following detailed description, when considered in connection with the accompanying drawings. Non-limiting and non-exhaustive embodiments of the present disclosure are described with reference to the following figures, wherein like numerals refer to like parts throughout the various views unless otherwise specified.

FIG. 1 is a perspective view of a partial representative towel with the terry fabric construction according to a first embodiment;

FIG. 2 is a weave design schematic according to the first embodiment;

FIG. 3 is a partial, three-dimensional, not-to-scale view of the weave components of the terry fabric according to FIG. 1;

FIG. 4 is a technical card including specifications of the representative towel of FIG. 1; and

FIG. 5 is a table including weight calculations based on the specifications of the technical card of FIG. 4.

DETAILED DESCRIPTION

In the following description, numerous specific details are set forth in order to provide a thorough understanding of the

present invention. It will be apparent, however, to one having ordinary skill in the art that the specific detail need not be employed to practice the present invention. In other instances, well-known materials or methods have not been described in detail in order to avoid obscuring the present invention.

Reference throughout this specification to “one embodiment”, “an embodiment”, “one example” or “an examples” means that a particular feature, structure or characteristic 10 described in connection with the embodiment of example is included in at least one embodiment of the present invention. Thus, appearances of the phrases “in one embodiment”, “in an embodiment”, “one example” or “an example” in various 15 places throughout this specification are not necessarily all referring to the same embodiment or example. Furthermore, the particular features, structures or characteristics may be combined in any suitable combinations and/or sub-combinations in one or more embodiments or examples. In addition, it is appreciated that the figures provided herewith are 20 for explanation purposes to persons ordinarily skilled in the art and that the drawings are not necessarily drawn to scale.

The present disclosure particularly describes a terry fabric having a different pile weight on each face of the fabric. Despite the differing pile weight on each face of the fabric, 25 the fabric may have the same pile height on both faces. Thus, the fabric of the present invention achieves a high-volume appearance towel with low overall weight. This construction provides effective absorption on the top surface, which may be used primarily for drying, while the bottom surface may 30 be used for rubbing or other action that requires more friction. These two different surfaces are provided in a single towel, fulfilling the complete purpose for which a towel is needed. The low overall weight of the fabric decreases the cost of laundering articles made of the fabric. However, the 35 face of the fabric used for drying feels luxurious to the user, so the user experience is not negatively affected. Additionally, the fabric remains versatile for manufacturing purposes. For example, any border may be used on an article made 40 from the fabric because the pile weight is consistent across a single face of the fabric.

Referring now to FIG. 1, a perspective view of a representative towel with the terry fabric construction according to a first embodiment is shown. With this fabric construction, the surfaces of towel 100 appear to have different 45 volumes, rather than a uniform volume on both surfaces of the fabric. This is possible by using a coarser/heavier yarn on a top surface 102 and a thinner/lighter yarn on a bottom surface 104. However, it will be understood that in other embodiments, a fabric construction may be used such that 50 surfaces of towel 100 appear to have the same volume, despite varying differing pile weight on each surface. This is achieved by using a fabric with the same pile height on both surfaces 102, 104.

The thinner yarn is conditioned before processing in the 55 warping stage, and a special tension adjustment on looms is used. The thinner yarn is scoured to remove the color from the yarn, so that it may be differentiated from the coarser yarn during the weaving process. After being scoured, the thinner yarn is then laid on warper reed with the thicker yarn 60 with a draw-in one by one, keeping this order on sizing stage and weaving. This process of scouring permits both type of yarns used for the fabric construction, making it easier to direction them on the corresponding shafts of the loom, whose movement determines pile formation on each surface 65 of the fabric.

Referring now to FIG. 2, a weave design schematic according to the first embodiment is shown. The schematic

200 includes weave design, pattern or shaft movement order, draw-in on shaft and reed. Ground ends are disposed with a straight draw, allowing a variety of designs on borders, just modifying the pattern on this area of the fabric.

Referring now to FIG. 3, a partial, three-dimensional, not-to-scale view of the weave components of the terry fabric according to FIG. 1 is shown. The weave **300** is a three-pick pile cycle terry weave. Ground warp ends E1 and E2 are comprised of a first yarn **302**. Top pile end E3 is comprised of a second yarn **304**, which may be a coarse 10 yarn. Bottom pile end E4 is comprised of a third yarn **306**, which may be thinner yarn than second yarn **304**. Ground fill picks P1, P2, and P3 are comprised of a fourth yarn **308**.

Referring now to FIG. 4, a technical card including 15 specifications of the representative towel of FIG. 1 is shown. Technical card **400** meets main specifications of towel **100**, which determines length, width and weight. It also contains the type of ends used on warp and weft, and their respective densities. For example, in the illustrated embodiment, the top pile yarn (e.g., second yarn **304** of FIG. 3) is 12s cotton 20 yarn, and the bottom pile yarn (e.g., third yarn **306** of FIG. 3) is 16s cotton yarn. It will be understood that the specifications on technical card **400** could be modified depending on the desired final weight and dimension of towel **100**. The specifications shown in FIG. 4 are for illustrative purposes 25 only and are in no way limiting.

Referring now to FIG. 5, a table including weight calculations based on the specifications of the technical card of FIG. 4 is shown. In the illustrated embodiment, table **500** shows the final weight of towel **100** is 14.04 pounds/dozen, with a top weight of 16.3 pounds/dozen and a bottom weight of 11.78 pounds/dozen, based on the use of 12s and 16s cotton yarns for the top and bottom pile yarns, respectively. Thus, the total weight of the towel is less than two times the 35 weight of the heavier surface but greater than the weight of the lighter surface. Therefore, although the overall weight of the towel is about 14 pounds, it has the quality of an approximately 16-pound towel on one face and an approximately 12-pound towel on the reverse face. Thus, the towel may be sold having the value of 16-pound towel for the price 40 of a 14-pound towel.

It will be understood that the calculations in table **500** are based on specifications of technical card **400** of FIG. 4, and that such calculations would change as the specifications of technical card **400** are modified. For example, the desired 45 overall weight of the towel (or other article) may be more or less than 14 pounds, as shown, and therefore varying the desired overall weight of the towel would require adjustments of all other values, all of which may be completely customizable. The calculations shown in FIG. 5 are for 50 illustrative purposes only and are in no way limiting.

While the foregoing descriptions have discussed towels, it should be recognized that the fabric of the present invention may be used for any suitable linen or item of manufacture for which terry cloth is or could be used.

Although specific features of various embodiments of the disclosure may be shown in some drawings and not in 55

others, this is for convenience only. In accordance with the principles of the disclosure, any feature of a drawing or other embodiment may be referenced and/or claimed in combination with any feature of any other drawing or embodiment.

5 This written description uses examples to describe embodiments of the disclosure and also to enable any person skilled in the art to practice the embodiments, including making and using any articles or systems and performing any incorporated methods. The patentable scope of the disclosure is defined by the claims, and may include other examples that occur to those skilled in the art. Such other examples are intended to be within the scope of the claims if they have structural elements that do not differ from the literal language of the claims, or if they include equivalent structural elements with insubstantial differences from the literal language of the claims.

What is claimed is:

1. A terry fabric consisting of:
a top surface having a top pile yarn with a single first pile weight and a single first pile height throughout the top surface; and
a bottom surface opposite the top surface having a bottom pile yarn with a single second pile weight and a single second pile height throughout the bottom surface, wherein:
the top pile yarn is greater in thickness than the bottom pile yarn;
the first pile weight is greater than the second pile weight;
the first pile height is equal to the second pile height; and
a combined weight of the top surface and the bottom surface of the terry fabric is less than two times the first pile weight but greater than the second pile weight.

2. A method of weaving terry fabric, the method consisting of:
scouring a bottom pile yarn; and
weaving the bottom pile yarn together with a top pile yarn, wherein the top pile yarn is thicker than the bottom pile yarn, to form a terry fabric having a top surface opposite a bottom surface, wherein the top pile yarn forms the top surface with a single first pile weight and a single first pile height throughout the top surface, the bottom pile yarn forms the bottom surface opposite the top surface having a single second pile weight and a single second pile height throughout the second surface, the first pile weight is greater than the second pile weight, and wherein the single pile height of the top surface is equal to the single pile height of the bottom surface and a combined weight of the top surface and the bottom surface of the terry fabric is less than two times the first pile weight but greater than the second pile weight.
